UNITED STATES PATENT OFFICE.

JAMES O'HALLORAN, OF IROQUOIS FALLS, ONTARIO, CANADA.

RELEASEABLE STAKE POCKET FOR RAILWAY CARS.

Application filed October 13, 1923. Serial No. 668,349.

To all whom it may concern:

Be it known that I, JAMES O'HALLORAN, a subject of the King of Great Britain, and residing at Iroquois Falls, Province of Ontario, Dominion of Canada, have invented certain new and useful Improvements in Releasable Stake Pockets for Railway Cars; and I do hereby declare the following to be a full, clear, and exact description of the same.

My invention relates to the stake portion of railway cars and especially to the pockets for securing the stakes of railway cars in position; the invention appertains particularly to pockets of the releasable type adapted to permit the stake being automatically displaced for the discharge of the contents of the car.

With cars transporting loose commodities such as logs, the load is maintained upon the car by side stakes, and is discharged by the expedient of freeing the stakes so that the weight of the load displaces the stakes and spills over the side of the car. In view of this the pockets for the lower ends of the stakes have been made displaceable and secured in stake retaining position by a trip device which can be released to free the pocket and permit the stake to be displaced under the outward urge of the load. In an arrangement of this nature where the load such as logs is utilized to displace the freed pocket and kick the stake away from restraining position the device is naturally subject to considerable strain and rough usage and it is therefore the primary object of the invention to improve existing devices of this character by the production of a simplified arrangement of a minimum number of parts capable of sturdy construction resulting in a more rugged arrangement than heretofore.

A further object is to provide a stake of special construction to protect it from excessive wear.

The above with additional objects and advantages will be hereinafter more fully described and particularly pointed out in the appended claims.

For full comprehension, however, of my invention reference should be had to the accompanying drawings forming a part of this specification, in which the same reference characters indicate the like parts and wherein:

Fig. 1 is a side elevation of a portion of a railway car with my improved attachment applied thereto;

Fig. 2 is a section on line 2—2 Fig. 1, showing the pocket locked in stake retaining position;

Fig. 3 is a side view similar to Fig. 2 with the pocket and stake released; and

Fig. 4 is a plan viewed as indicated at 4—4 Fig. 2.

In the drawings I have illustrated my invention as applied to a logging car, the floor of which is indicated at 2 and supported upon the longitudinally extending beams 3. Stakes 4 are arranged at suitable distances along the car side and at each of these locations my improved pocket is disposed. Each stake pocket consists of an upright inwardly facing U-shaped pocket member 5 pivoted at the bottom at 6 to the car structure at a point below the floor thereof a sufficient distance to permit the pocket member swinging outwardly and downwardly free of the bottom end of the stake which the pocket member embraces when in its upright or closed position holding the stake in place.

The pocket member is locked in closed position by a latch 7 pivoted at 19 to the car structure at a point inside the stake line and having its free end formed to engage the upper or free end of the pocket member. This locking engagement of the latch with the pocket member is maintained by a vertically slidable bolt 8 engaging the underside of the latch between the ends and being upheld by a lever 9 engaging its lower end. Lever 9 is pivotally supported by the car structure on the pivot 6 near the side of the car and extends inwardly beneath and in engagement with bolt 8, the inner free end of the lever being loosely supported upon a crank arm 10 formed upon a shaft 11 extending longitudinally under and supported by the car structure. Rotation of shaft 11 withdraws crank 10 from beneath lever 9 permitting the latter to swing down and thereby lowering bolt 8 thus permitting latch 7 to disengage from pocket member 5 to unlock the latter and permit it to swing free of the stake, to release the latter.

The engagement of latch 7 and pocket member 5 is secured through the medium of correspondingly inclined surfaces which, upon the lowering of bolt 8, are free to slide

out of engagement, this arrangement translating the outward urge of the load into a downward force upon the latch thus utilizing the force of the load upon the stake to 5 automatically unlock the pocket member, free the stake and displace the latter for the discharge.

The detail arrangement is as follows:

A supporting bracket 12 is bolted at 12^a 10 to the outer side of the outside stringer 3^a of the car, the bracket being formed with top and bottom flanges 13 and 14 respectively extending over and under the beam, the whole forming a U-shaped saddle vertically straddling the beam from the outside and held securely thereto by the bolts 12^a, the heads of which are located in depressions formed in the vertical margins of the bracket so as not to project outwardly from 15 the bracket. The flanges 13 and 14 have vertical openings 15 therethrough registering with a vertical passage through the outside stringer and constituting a guide way for bolt 8 which extends downwardly there- 20 through, the floor of the car being cut away to accommodate the flange 13 and bolt 8.

The lower end of the bracket is formed with depending apertured lugs 16 on opposite sides and spaced from each other to 25 form bearings for a pin 6 upon which the lower end of the pocket is mounted, the lower end of the pocket being bifurcated at 16 and apertured to receive the pin thus forming the pivotal support of the pocket.

30 The pocket member 5 extends from its pivoted end across the bracket upwardly a suitable distance above the floor level of the car and is substantially U-form in cross-section from its upper open end to a point 35 near the bottom of the bracket for the accommodation of the stake and the outer face of the bracket has a corresponding vertical concavity to co-operate with the pocket member in the accommodation of the stake.

40 An interior transverse ledge or shoulder 17 is formed near the bottom of the pocket member upon which the lower end of the stake is adapted to be supported. It is preferred to have the co-operating concavities 45 of the bracket and pocket curved in cross-section as it has been found that a round metallic stake is preferable to the irregular wooden stake inasmuch as the latter is more subject to wear and the danger 50 of splitting, especially from the upper end, is greatly increased. For this reason I have found that the most efficient stake is a metallic one surmounted by a conical cap 4^a, the 55 tapered top deflecting any object which 60 might otherwise strike solidly upon and injure the stake.

The upper end of the pocket member has outwardly extending lugs 18 at its free inner edges and the latch 7 is preferably in 65 the form of a plate mounted upon a pin 19

at its inner end, the pin bearing at its inner ends in cross beams 20 of the car. The outer or free ends of the latch is bifurcated to straddle the upper end of the pocket member when the latter is in its upright or closed 70 position, the legs 21 of the latch being formed with upwardly extending lugs 22 adapted to slide upwardly into engagement with the lugs 18, when the pocket member 75 is in its upright position. The lugs 18 present outwardly facing and downwardly and inwardly inclined surfaces 23 while the lugs 22 present inwardly facing and upwardly and outwardly inclined surfaces 24 so that 80 when the latch is raised into locking position with the pocket member the surfaces 23 and 24 slide over each other and draw the pocket member snugly inwardly about the stake while in the releasing movement the co-operating inclined surfaces cause the 85 outward urge exerted upon the pocket member by the outwardly directed force of the load upon the stake, to be translated into a downward force positively and automatically freeing the latch from the pocket member. This accelerates the stake releasing 90 movement of the pocket member and this acceleration is augmented by the position of pivot 6, the lower end of the pocket member being inwardly offset to so dispose the pivotal point 6 as to avoid dead centre retardation in the swinging movement of the 95 pocket member.

The bolt supporting lever 9, is also pivoted upon pin 6, the outer end of the lever being mounted upon the pin between the legs 16 of the pocket member and extending therefrom in a slight arc to a point beneath the floor beams of the car when its inner free end rests upon the before mentioned crank arm 10 constituted by a flattened and laterally extended portion of shaft 11 which latter is mounted in bearings 25 suspended from one of the beams. The shaft 11 preferably extends between two stakes and is provided with two crank portions so that the two stakes can be operated at one time, the shaft being oscillated by a lever arm 26 fixed thereto and extending downwardly therefrom. For convenience the lever arm is actuated by an operating bar 27 connected at its inner end to the lower end of the lever arm 26 and extending outwardly therefrom to the opposite side of the car where it is fixedly supported by a bracket 28 in a manner whereby it can be readily released for operation.

Prior to loading the car the stakes are positioned with the pocket members enclosing them and the lever 9 set to uphold the bolts 8 and maintain the latch in locking engagement with the pocket members, the operating bar 27 being fixed to its bracket to avoid accidental releasing movement. The car is then loaded and when the discharge 100

point is reached, operating bar is released and pulled outwardly thus oscillating shaft 11 to withdraw crank 10 from beneath lever 9 and permit the latter to swing down for the lowering of bolt 8, the weight of the load against the stake automatically uplocking the pocket members, swinging the latter down and displacing the restraining stake. In the operation of cars of this type the 10 discharge side only of the car is usually provided with the releasable pocket members, the stakes on the opposite side being secured in the usual manner and having a chain 31 attached to the top and extending therefrom 15 to the top of the releasable stake opposite so that in discharging the load and releasing the lower end of the releasable stakes the upper end of the stake is flexibly held and the freed stake kicked upwardly out of 20 the way of the falling load. In my preferred construction the cap 4^a is formed with an eye for the convenient attachment of chain 31.

What I claim is as follows:

25 1. In a car the combination with longitudinal frame members and a pair of transverse load supporting members carried by and projecting beyond the longitudinal members, of a releasable stake holding device comprising a pocket member the lower end of which is offset to permit pivotal connection with one of said longitudinal members and the upper free end of which is formed for engagement by a latch when 30 in stake-holding position; a latch adapted to engage the free end of said pocket member, and means carried by the longitudinal members for operating the latch; the arrangement being such that all parts of the 35 device, when the pocket member has been released and swung down to its lowermost position, are entirely beneath the load bearing surface and inwardly away from the ends of said transverse members.

40 2. In a car the combination with longitudinal frame members and a pair of transverse load supporting beam members carried by and projecting beyond the longitudinal members, of a releasable stake holding device comprising a locking member the lower end of which is offset to permit pivotal connection with one of said longitudinal members and the upper free end of which is formed for engagement by a latch when 45 in stake holding position between the projecting ends of the transverse members; a latch located between and pivoted to said transverse members adapted by upward movement to engage the free end of the pocket member, and means carried by said longitudinal members for operating the latch; the arrangement being such that all the parts of the device, when the pocket member thereof has been released and 50 swung down to its lowermost position, are

entirely beneath the load bearing surface and inwardly away from the ends of said transverse members.

3. In a railway car, the combination with a stake, of a pocket embracing the lower end of the stake, such pocket being pivoted to the car structure at a point below the floor level and adapted to swing outwardly to release the stake and a locking device for holding the pocket in its stake retaining position including a latch pivoted to swing vertically and engage the upper end of the pocket, a device for positively upholding the latch and including a vertically slidable bolt engaging the underside of the latch, a lever upholding the bolt at its lower end, a crank shaft upholding the lever and means for oscillating the crank shaft to release the lever and permit the bolt to withdraw from upholding position with respect to the latch. 70

4. In a railway car, the combination with a stake, of a pocket embracing the lower end of the stake, such pocket being pivoted to the car structure to swing outwardly therefrom and comprising an elongated member of U-form in cross section, a latch pivoted to the car and adapted to engage with the pocket to hold same in stake retaining position, a vertically slidable bolt for locking the latch in engagement with the pocket and means for lowering and raising the bolt to alternately unlock and lock the latch. 85

5. In a car, a releasable stake supporting and holding device comprising a pocket member of oblong form, presenting an inner concave surface to accommodate a stake of tubular form and having its lower end offset to permit pivotal connection to the underframe of the car. 90

6. In a railway car, the combination with a stake, of a pocket embracing the lower end of the stake, such pocket being pivoted to the car structure at a point below the floor level and extending upwardly from the pivot point to a point above the floor level, the major portion of the pocket being substantially of U-form in cross-section and presenting an interior shoulder near the lower end for upholding the stake, lugs extending outwardly from the upper end of the pocket, a latch pivoted to the car structure inside the stake line and adapted to swing upwardly into engagement with the lugs of the pocket, a vertically positioned bolt slidably supported by the car structure with its upper end engaging the underside of the latch, a lever pivoted at one end to the car structure and having the lower end of the bolt supported thereby, an oscillatory shaft supported by the car structure and presenting a crank arm upon which the free end of the lever is upheld, a lever arm fixed to the shaft and an operating bar connected at one end to the lever arm where- 105

by the shaft is oscillated to withdraw the crank arm from supporting position with respect to the bolt supporting lever.

7. In a railway car, having a floor and floor beams including an outside stringer, with a vertical opening therethrough, a stake pocket construction comprising, a bracket presenting a concaved outer face and being bolted to the outer side of the outside stringer and presenting a vertically disposed concave outer face and top and bottom flanges lying over and under the stringer and presenting openings registering with the opening through the stringer, a stake pocket having a horizontal pivotal connection with the lower end of the bracket and extending upwardly across the latter, said pocket being of substantial U-form in

cross-section, with an interior transverse shoulder to co-operate with the concave surface of the bracket in the accommodation of the stake, a latch pivoted to the car structure and adapted to swing upwardly into engagement with the pocket, a bolt for upholding the latch in engagement with the pocket and means for supporting and lowering and raising the bolt to release and uphold the latch.

In testimony whereof, I have signed my name to this specification, in the presence of two subscribing witnesses.

JAMES O'HALLORAN.
